(57) **CLAIM**

The ornamental design for an extruded corner piece, as shown and described.

DESCRIPTION

FIG. 1 is a front isometric view of the extruded corner piece showing our new design in a state of use;

FIG. 2 is a front isometric view of the extruded corner piece shown in FIG. 1;

FIG. 3 is a rear isometric view of the extruded corner piece shown in FIG. 1;

FIG. 4 is a front view of the extruded corner piece shown in FIG. 1;

FIG. 5 is rear view of the extruded corner piece shown in FIG. 1;

FIG. 6 is a top view of the extruded corner piece shown in FIG. 1;

FIG. 7 is a bottom view of the extruded corner piece shown in FIG. 1;

FIG. 8 is a left side view of the extruded corner piece shown in FIG. 1; and,

FIG. 9 is a right side view of the extruded corner piece shown in FIG. 1.

The broken lines in the drawings represent portions of the extruded corner piece and form no part of the claimed design. The other broken lines represent environmental subject matter and form no part of the claimed design.
